(57) **CLAIM**

The ornamental design for a blister package, as shown and described.

DESCRIPTION

FIG. 1 is a top perspective view of a blister package according to the present invention;
FIG. 2 is a bottom perspective view thereof;
FIG. 3 is a top plan view thereof;
FIG. 4 is a bottom plan view thereof;
FIG. 5 is a front elevational view thereof;
FIG. 6 is a rear elevational view thereof;
FIG. 7 is a right side elevational view thereof;
FIG. 8 is a left side elevational view thereof; and
FIG. 9 is a top perspective view of a second embodiment of FIG. 1 with a protective lidding seal extending across an upper surface of the blister package;
FIG. 10 is a bottom perspective view of FIG. 9;
FIG. 11 is a top plan view of FIG. 9;
FIG. 12 is a bottom plan view of FIG. 9;
FIG. 13 is a front elevational view of FIG. 9;
FIG. 14 is a rear elevational view of FIG. 9;
FIG. 15 is a right side elevational view of FIG. 9; and,
FIG. 16 is a left side elevational view of FIG. 9.

Although the design is illustrated as transparent, the claimed invention may also be embodied as opaque. The broken line portion of the figure drawings is included to show unclaimed subject matter only and forms no part of the claimed design.

1 Claim, 10 Drawing Sheets
